UNITED STATES PATENT OFFICE.

LADISLAUS KARCAZAG, OF CHARLOTTENBURG, AND EDUARD KOPETSCHNI, OF MANNHEIM, GERMANY.

PROCESS FOR THE PRODUCTION OF ACID CHLORIDS OF THE OXYACIDS.

1,106,455.

Specification of Letters Patent.

Patented Aug. 11, 1914.

No Drawing.

Application filed September 5, 1912. Serial No. 718,643.

To all whom it may concern:

Be it known that we, Dr. LADISLAUS KARCAZAG and Dr. EDUARD KOPETSCHNI, both subjects of the King of Hungary, Emperor of Austria, residing, respectively, at 49 Schlueterstrasse, Charlottenburg, and 40 Kaiserring, Mannheim, both in the German Empire, have invented a certain new and useful Improvement in Processes for the 10 Production of Acid Chlorids of the Oxyacids, of which the following is a specification.

Anschutz in trying to produce the chlorids of the mono-oxybenzoic acids with phosphoric chlorids (*Liebigs Annalen* 239,301, etc.) has as is known, established the fact that it is not the simple acid chlorids but chemical compounds of a more complex nature that are formed, these compounds containing phosphorus and in which the chlorinating agent has entered the molecule of the oxyacids. In the comprehensive publication of these operations (R. Anschutz "Ueber ein Gesetz der Bildung freier Phenolkarbonsäurechloride", *Berichte* 30.221 (1897), the said author states that chlorids of the single phenol carboxylic acids cannot be produced in this way, the only exception being those oxy carbonic acids which 30 are substituted in the ortho position to the phenol hydroxyl and owing to this "protective action" of the substitute are capable of forming free phenol carboxylic chlorids (see also German Patent No. 89596).

35 The operations of Hans Meyer ("Ueber eine allgemein anwendbare Methode zur Darstellung von Chloriden der organischen Säuren", *Wiener Monatshefte* 22, 415/1901) in which he endeavored to utilize thionyl 40 chlorid as a generally utilizable chlorinating agent in substitution of carboxyl hydroxyl, curiously afforded an exception precisely for the mono-oxybenzoic acids. In the chlorination of the three isomeric mono-oxybenzoic acids by means of thionyl chlorid, H. Meyer ascertained that although m-oxy benzoic acid furnished the corresponding chlorid, salicylic acid after long continued boiling furnished a new chlorid 50 (not salicyl chlorid) but a sulfurous acid ester of salicyl chlorid of unknown constitution, while p-oxybenzoic acid does not re-

act at all with thionyl chlorid even after boiling for days.

If thionyl chlorid is caused to act on salicylic acid in the presence of tertiary bases, then in the manner described in German Patent No. 211403 anhydriding of the salicylic acid always takes place and (in this case) the formation of salicylo-salicylic acid. 60 The latter is also obtained according to the said patent by the action of not more than the theoretical quantity (a half molecule) of thionyl chlorid upon neutral and basic salicylates. Now the surprising fact has 65 been noted that by causing neutral salts of aromatic or alipatic oxy carboxylic acids to be acted upon by at least one molecule of an oxychlorid whose products of decomposition resulting from this reaction are gaseous at ordinary temperature the chlorids of the corresponding oxy acids are at once reached. Thus, for example, the neutral salts of salicylic acid of the type $C_6H_4(OH)COO M$ (M being a metal), in contradistinction to the free acid, react with thionyl chlorid in excess readily in a cold state in forming the long-sought-for salicylic chlorid, which latter differs distinctly from Meyer's "sulfurous acid ester of salicylic chlorid" in its properties. If on the other hand, thionyl chlorid is caused to act 70 on basic salicylates (sodium di-salicylate for example), but small quantities of chlorid are obtained and principally other products, 75 which have not been closely examined, are 80 formed.

In a similar manner the salts of m- and p-oxybenzoic acid react with thionyl chlorid so that m- and the hitherto unknown p-oxybenzoyl chlorid are formed. Likewise (in order to adduce an example from the aliphatic series also) when thionyl chlorid acts on salts of glycolic acid, glycolic chlorid, which has not hitherto been known in 95 a pure form, is produced (*Journ. prakt. Chem.* 7.343.).

The reaction of thionyl chlorid generally takes place more readily with the salts of the oxy-carboxylic acids and at lower temperatures than the action on the free acids. In view of the decomposibility of the chlorids obtained and the fact that under the influence of the thionyl chlorid in excess 100

the latter are apparently further modified in part the advantage results that by employing the salts purer products are obtained. Thus the preparation of m-oxy benzoyl chlorid from the salts presents the advantage as compared with the employment of free m-oxybenzoic acid (according to H. Meyer) of rendering it possible to operate with the theoretical quantity of thionyl chlorid at a low temperature and consequently to repress the formation of sulfurous acid ester which otherwise forms as a by-product. Phosgene can also be used instead of thionyl chlorid.

The chlorids of the oxy acids thus produced are generally very freely capable of reacting but are also partially sensitive bodies. Salicylic chlorid for example forms at ordinary indoor temperatures an oily colorless liquid of a characteristic but not unpleasant smell. In a cooling mixture the oil sets into a crystalline mass of felted or matted well-defined white needles which melt at about 9° to 11° C. Upon distillation (also *in vacuo*) the salicylic acid chlorid decomposes in separating hydrochloric acid. Mixed with methylalcohol Gautheria oil (methyl salicylate) with its very characteristic odor forms at once and salicylic ethyl-ester forms with ethyl alcohol. Caused to react with anilin salicylic anilid is formed which is identical with that already described in technical literature which is obtained in a different way. Meta and para oxy benzoyl chlorid are tear-inducing strongly smelling oils which do not set even in a cooling mixture of 15-20° C. Chemically they behave like salicylic chlorid and are also decomposable. When treated with methyl alcohol abs. (in which a vigorous reaction begins even at ordinary indoor temperature) the corresponding methyl esters of m- and p-oxy benzoic acid are formed. Glycolic acid chlorid, which has hitherto not been known, is a penetratively acid smelling colorless oil.

Examples.

1. 16 parts of soda salicylate are introduced into 25 parts of thionyl chlorid in small portions. In developing sulfurous acid a vigorous reaction takes place. It is preferable to provide that a heating of the reaction mass over 30° does not take place. The reaction takes place in accordance with the following equation.

The reaction is finished as soon as the development of sulfurous acid ceases. The thionyl chlorid in excess is then distilled over *in vacuo* and the salicylic chlorid formed is removed from the residuum by means of neutral solvents having a low boiling point, such for example as carbonic

disulfid or ligroin. The solvent is then driven off completely by distillation *in vacuo* at as low a temperature as possible, the salicylic chlorid remaining behind as an oily liquid.

2. To a mixture of 110 g. of thionyl chlorid and 120 ccm. of benzol 100 g. of sodium salicylate are added gradually in slowly shaking the liquid. The reaction mass swells into a colloidal mass which is allowed to stand for an hour in a cold temperature. Thereupon the unutilized thionyl chlorid and the benzol are distilled over in a rarefied chamber and the residuum leached with benzol. The solution of the salicylic acid chlorid in benzol is then again freed from the solvent *in vacuo*, the operation being carried out with a high vacuum and low temperature. The yield amounts to approximately 85-90% of the theoretical yield, relatively to the salt used.

3. For the production of m-oxy benzoyl chlorid 15 g. of sodium m-oxy benzoate in the finest state of pulverization are slowly introduced into 60 g. of thionyl chlorid, the temperature of the reaction mass being kept low by cooling with ice. As soon as the salt is consumed, the thionyl chlorid in excess is at once distilled over *in vacuo* as by its action when the reaction is terminated apparently a further modification of the chlorid formed is produced. The residuum is extracted with low boiling ligroin, the solution is filtered and then the m-oxy benzoyl chlorid is freed *in vacuo* from ligroin.

4. 20 g. of potassium p-oxy benzoate are slowly introduced in a finely pulverized form into 60 g. of thionyl chlorid in small portions. In order to moderate the reaction, which commences violently, the reaction vessel is cooled with ice. The potassium chlorid separates out in a white amorphous and voluminous form. When the first operation is finished, the thionyl chlorid in excess is immediately distilled over in the rarefied chamber, and the p-oxy benzoyl chlorid is extracted from the residuum by means of ligroin, this chlorid remaining behind as a strongly-smelling yellowish oil after the elimination of the solvent.

5. Phosgene is introduced preferably into an ice-cooled suspension of salicylate of sodium in a small quantity of benzol (toluol and so forth) or the sodium salicylate is introduced into toluol saturated with phosgene and the mixture is then left for some hours. The further treatment is identical with that already described in connection with thionyl chlorid.

6. The process for the formation of glycolic chlorid is quite analogous to the examples already described. 20 g. of soda glycolate are gradually introduced into 100 g. of thionyl chlorid and in order to prevent excessive heating of the reaction mass, simul-

taneously cooled with ice. The excess is distilled over with thionyl chlorid, extraction with ligroin is then effected and the latter is then driven off *in vacuo* in the manner repeatedly described above. The colorless, oily glycolic chlorid remains in the residuum.

What we claim and desire to secure by Letters Patent of the United States is:

1. The process for the manufacture of acid chlorids of the oxy acids which consist in causing one molecule of a neutral salt of an oxy carboxylic acid to be acted upon by at least one molecule of an oxychlorid whose products of decomposition resulting from this reaction are gaseous at ordinary temperature.

2. The process for the manufacture of acid chlorids of the oxy acids, which consists in causing at least one molecule of thionyl chlorid to act upon one molecule of a salt of an oxy carboxylic acid.

3. The process for the manufacture of salicylic acid which consists in causing one molecule of a neutral salicylate to be acted upon by at least one molecule of an oxychlorid whose products of decomposition resulting from this reaction are gaseous at ordinary temperature.

4. The process for the manufacture of salicylic chlorid which consists in causing at least one molecule of thionyl chlorid to act upon one molecule of a neutral salicylate.

5. The process for the manufacture of acid chlorids of the oxyacids which consists in causing one molecule of a neutral salt of an oxy carboxylic acid to be acted upon, in

the presence of an indifferent diluent, by at least one molecule of an oxychlorid whose products of decomposition resulting from this reaction are gaseous at ordinary temperature.

6. The process for the manufacture of salicylic chlorid which consists in causing at least one molecule of thionyl chlorid to act upon one molecule of a neutral salicylate in the presence of an indifferent diluent.

7. The process for the manufacture of salicylic chlorid which consists in gradually introducing 16 parts of sodium salicylate into 25 parts of thionyl chlorid, distilling over the thionyl chlorid in excess *in vacuo*, removing the salicylic chlorid formed from the residuum by means of a neutral solvent and driving the solvent off by distillation *in vacuo*.

8. The herein described product consisting of salicylic acid chlorid, the same being an oily colorless liq id forming, when cooled, white needles melting at from 9 to 11 degr. C., decomposing upon distillation, even *in vacuo*, forming when mixed with ethyl alcohol, salicylic ethyl ester.

In testimony whereof we affix our signatures in presence of two witnesses.
